CLAIM

The ornamental design for an eyeglass frame, as shown and described.

DESCRIPTION

FIG. 1 is a Perspective View of the eyeglasses of the present invention;

FIG. 2 is a Front View;

FIG. 3 is a Plan View thereof;

FIG. 4 is a Right Side View thereof;

FIG. 5 is a Rear View thereof;

FIG. 6 is an Inverted Plan View thereof; and,

FIG. 7 is a Perspective View of the eyeglasses of the present invention with a portion of the nosepiece shown in phantom.

The phantom showing of a portion of the nosepiece is for illustrative purposes only and forms no part of the claimed design.
